DRAIN PAN

George Raymond Lindahl, Los Angeles, Calif.

Application November 19, 1940, Serial No. 366,305

6 Claims. (Cl. 62—1)

This invention relates to drain pans for use in connection with refrigerating units, one of the objects being to provide a drain pan which, when supported beneath the evaporator of a refrigerating or cooling apparatus, will operate efficiently to collect water gravitating from the evaporator and, at the same time, present the minimum of restrictions to the movement of air from the coil or evaporator.

A further object is to provide a drain pan permitting free flow of air sideways as well as downwardly whereby the air can move more rapidly from the evaporator and drain than has been possible heretofore so that lower temperatures are insured within the refrigerator or other enclosure containing the improvement.

A further object is to provide a drain pan the construction of which results in increased efficiency of the evaporator due to the fact that the free and rapid downward movement of the air from the evaporator acts to accelerate the upward movement of the warm air displaced thereby, thus resulting in more air passing over the evaporator and more heat being extracted from the structure in a given length of time than has been possible heretofore.

A still further object is to provide a drain pan the parts of which are assembled readily and are held in proper position without the use of screws, bolts, insulators, or other mediums for the separation of the units of the pan or for affording insulation between the various parts.

Another object is to provide a drain pan which reduces the possibility of condensation at the bottom of the pan and which, by retaining a certain amount of water by capillary attraction, acts to wash the air circulating through the pan so as to absorb gases and odors from the air.

Another object is to provide a drain pan the parts of which can be carried in stock sizes so that replacements can be made readily and orders for pans of different sizes can be filled quickly without the use of special tools and without requiring the services of skilled mechanics.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing:

Figure 1 is a front elevation of a drain pan constructed in accordance with the present invention.

5 Figure 2 is a top plan view, portions being broken away.

Figure 3 is an end elevation, portions being broken away.

10 Figure 4 is a detail view of a portion of one edge of a trough and that portion of a cross-bar in engagement therewith.

Referring to the figures by characters of reference, 1 designates cross-bars in the form of flat strips of material, preferably aluminum, these bars being spaced apart desired distances and being connected, adjacent to their ends, by tie rods or bolts 2 which, in turn, can be engaged by hangers or other suitable supporting means not shown.

20 Recesses 3 are extended upwardly into each cross-bar, these recesses being spaced apart equal distances. Each recess is formed preferably with parallel side walls 4 perpendicular to the bottom edge of its bar while the top of each recess is defined by upwardly converging walls 5.

Short slots 6 are extended into each bar 1 from the upper ends of the walls 4, these slots diverging upwardly, and similar slots 7 are extended into each bar 1 from the lower ends of the walls 4, these slots 7 likewise diverging upwardly.

Extended downwardly into each bar 1 are slots 8 disposed in pairs, the slots of each pair diverging downwardly at points equidistant from an imaginary line perpendicular to the top of the bar and extending between and equidistant from two of the recesses 3. This imaginary line has been indicated at L.

By extending the slots 8 into the bars, they cooperate with the top edges of the bars to define short tongues 9 and similar tongues 10 are defined by the slots 7 and the bottom edges of the bars 1.

In addition to the cross-bars 1 and their connections 2, the pan comprises superposed troughs 11 and 12 and deflecting baffles 13. The troughs and deflecting baffles are all preferably of the same shape and size and are all preferably formed of a suitable metal, such as aluminum. Each of them is of such length as to extend throughout the length of the pan and each of them is bowed transversely but straight from end to end.

55 Strips of material from which the troughs and deflecting baffles are to be made can be kept in stock and cut to any lengths desired in order

to produce pans of the proper proportions. After these parts have been cut to the proper lengths some of them are inserted longitudinally in the slots 6 in strips 1 so as to be supported in these slots and across the upper portions of the recesses 3 with their concave faces uppermost. Thereafter other strips of the material are slid longitudinally into the slots 1 so as to be in engagement with and supported by all of the bars 1 below and parallel with the upper strips or troughs 11 and likewise bridging the recesses 3. Additional strips of the material are then inverted so that their convex surfaces will be uppermost and these strips are inserted longitudinally into the slots 8 of the bars 1. The respective ends of the troughs and baffles are positioned in the same plane and after all of the parts have thus been brought together the assembly is completed by slightly offsetting the tongues 9 and 10 so as to cause them to pinch and hold the adjacent parts of the pan elements seated in the slots. Thus the parts are held together without the use of screws, pins, solder or the like and obviously pans of different sizes can readily be made simply by increasing or reducing the number of troughs and baffles and increasing or reducing the length of these parts.

By locating the slots 8 so that they overlie the slots 6 and 1, the baffles 13, when properly positioned, will bridge the spaces between the recesses 3 and will overlap the adjacent troughs 11.

Small openings 14 can be provided in the upper troughs 11 at desired points so that water directed into these troughs will be free to drain into the lower troughs 12.

After a pan of proper size has been assembled, the same is supported under the evaporator or coils of a refrigerator so that water dripping therefrom must fall upon some part of the pan. Water which does not fall directly into the troughs 11 will drop onto the deflecting baffles 13 and drain laterally therefrom into the troughs 11. From these troughs the water will drain through the openings 14 into the lower troughs 12. Here the water will build up to a certain depth due to capillary attraction of the metal for water and when said depth is reached, the weight of the water will overcome the capillary attraction of the metal and cause the water to be abruptly discharged from the end or ends of the trough.

When a pan such as herein described is used, cold air flowing downwardly from the evaporator will be practically free from obstruction and can move downwardly and sideways over the baffles and over and between the troughs, this flow being so rapid that the warm air will be more quickly displaced than ordinarily and forced upwardly more rapidly than usual so as to come into contact with the evaporator and increase the efficiency of the refrigerating unit. As the troughs 12 are provided at all times with small amounts of water, this water as well as that dripping from the edges of the baffles 13 and flowing through the openings 14 will act to wash the air flowing between the parts, thereby absorbing gases and odors from the air.

It has been found in practice that a drain pan, such as herein described is advantageous not only because of the ease with which it can be made in all desired sizes but also because it accelerates the flow of air in a refrigerator by offering minimum resistance or restriction to the movement of the air. The pan is also advan-

tageous because in practice it has been found that no water of condensation will accumulate on the bottoms of the lower troughs. This is due to the fact that air circulating between the upper and lower troughs acts as an insulating means which brings the temperature of the bottom troughs to that of the falling air stream and, consequently, the lower troughs will not sweat under the most adverse conditions. It might be stated, furthermore, that because of this advantageous result, the pan can be supported more closely to the evaporator without sweating than can other construction and, as a result, more space is left in the refrigerator for storage purposes.

What is claimed is:

1. A drain pan including superposed spaced troughs arranged in laterally spaced pairs, the upper troughs having drain openings, arcuate baffles bridging the spaces between said pairs and overlapping the upper troughs, spaced bars engaged by and connecting the side edges of the troughs and baffles, there being recesses in the bars bridged by the troughs.

2. A drain pan including superposed spaced troughs arranged in laterally spaced pairs, the upper troughs having drain openings, arcuate baffles bridging the spaces between said pairs and overlapping the upper troughs, spaced bars engaged by and connecting the side edges of the troughs and baffles, there being recesses in the bars bridged by the troughs, and connections between the bars.

3. A drain pan including spaced bars having spaced recesses extending thereinto from their lower edges, there being pairs of diverging slots extending upwardly from the sides of the recesses and downwardly diverging slots in the top edges of the bars, superposed troughs bridging the recesses and having their side edges seated within the slots extending from the recesses, inverted arcuate baffles having their side edges seated in the top slots, said troughs and baffles being in engagement with and supported by all of the bars.

4. A drain pan including spaced bars having spaced recesses extending thereinto from their lower edges, there being pairs of diverging slots extending upwardly from the sides of the recesses and downwardly diverging slots in the top edges of the bars, superposed troughs bridging the recesses and having their side edges seated within the slots extending from the recesses, inverted arcuate baffles having their side edges seated in the top slots, said troughs and baffles being in engagement with and supported by all of the bars, the top and bottom edges of each bar and the slots extending into said edges cooperating to provide bendable gripping tongues.

5. A drain pan including spaced bars having spaced recesses extending thereinto from their lower edges, there being pairs of diverging slots extending upwardly from the sides of the recesses and downwardly diverging slots in the top edges of the bars, superposed troughs bridging the recesses and having their side edges seated within the slots extending from the recesses, inverted arcuate baffles having their side edges seated in the top slots, said troughs and baffles being in engagement with and supported by all of the bars, said baffles bridging the spaces between the recesses and having their side edges overlying and spaced from the adjacent troughs.

6. A drain pan including thereinto from their spaced recesses extending

lower edges, there being pairs of diverging slots extending upwardly from the sides of the recesses and downwardly diverging slots in the top edges of the bars, superposed troughs bridging the recesses and having their side edges seated within the slots extending from the recesses, inverted arcuate baffles having their side edges seated in the top slots, said troughs and baffles being in

engagement with and supported by all of the bars, said baffles bridging the spaces between the recesses and having their side edges overlying and spaced from the adjacent troughs, there being 5 drain openings in the upper troughs, and means for connecting the bars and engaging a stand support.

GEORGE RAYMOND LINDAHL.
